UNITED STATES PATENT OFFICE.

EMIL E. STOSSEN, OF WHITE PLAINS, NEW YORK.

COMBINED DUSTPAN AND HOLDER FOR BROOMS, ETC.

1,402,547.

Specification of Letters Patent.

Patented Jan. 3, 1922.

Application filed May 24, 1919, Serial No. 299,393. Renewed June 1, 1921. Serial No. 474,295.

To all whom it may concern:

Be it known that I, EMIL E. STOSSEN, a subject of the Government of Germany, residing at White Plains, in the county of 5 Westchester and State of New York, have invented certain new and useful Improvements in Combined Dustpan and Holder for Brooms, Etc., of which the following is a specification.

10 This invention relates to an improvement in a combined dust-pan and holder for brooms and the like, it has for its primary object the provision of a device which, by its particular construction, will be closely associated 15 with the broom or brush when placed in storage by being used as a hanger for the same.

A further object is in the provision of a device which may be cheaply manufactured, 20 simple in construction, durable and conveniently manipulated to serve the dual use for which it was designed.

A further object is in the provision of means which may be readily attached to the 25 dust-pan when it is desired to support a brush therefrom.

The invention further consists in the features and construction of parts fully described and pointed out in the following 30 description and claims.

In the accompanying drawing in which like reference numerals designate like parts throughout the various views, Fig. 1 is a perspective of one form of device as viewed 35 from the underside; Fig. 2 is a sectional detail showing the manner in which the broom is suspended therefrom; Fig. 3 is a front elevation; Fig. 4 is a sectional detail of a modified form showing the manner in which 40 a floor brush is suspended therefrom; Fig. 5 is a front elevation of the device as viewed from the left of Fig. 4; Fig. 6 is a perspective view of a clip to be attached to the dust-pan as shown in the preceding figures; Fig. 7 45 is a perspective view of a clip to be used for supporting a brush or broom by the handle and Fig. 8 is a detail showing the method in which this device is used.

Referring particularly to the drawing the 50 device as shown in Figs. 1 to 3 comprises a pan or scoop A formed of sheet metal, preferably tapered from the top to the bottom end, and in the illustrations I have shown a scoop composed of a bottom 1 having pressed 55 upwardly therefrom sides 2—2 and one end wall 3, and the other end of the device is

open to allow for the sweeping of dust and other refuse into the pan or scoop. The corners formed by the junction of the walls 2 and 3 are preferably rounded, as are the 60 corners formed at the bottom and side walls. This construction enables the user to thoroughly clean the scoop after use and prevents refuse from lodging in the corners thereof, thus a sanitary construction is obtained. 65

A sheet metal handle 4 is formed in two halves which are substantially semi-cylindrical, and the lower half has projecting therefrom a flat horizontal flange 5, the upper half has a similar flange 6, but formed 70 at right angles to the handle, and after the opened sides of the two halves are joined in any suitable manner, such as soldering, the handle is secured to the scoop by having the aforementioned flanges riveted thereto as 75 shown at 7. This provides a rigid construction not easily damaged. Apertures 8 in the upper end of the handle provide a convenient means whereby the device may be hung upon a nail driven into a wall or the like. 80

For convenience in supporting the broom or the like an opening 9 is provided in the end wall 3 immediately above the flange 6 of the handle, and the broom being turned head up, it is merely necessary to insert the 85 handle thereof into the aforementioned opening. This arrangement will be found most satisfactory as the broom may be easily removed without disturbing the pan.

In Figs. 4 to 6 inclusive is shown a modified form of a dust-pan of substantially the same construction, like reference numerals being used to designate similar parts. In this form the handle 4^a is made of a single piece of metal rolled into conical form and 90 flattened at its smaller end as at 13, and thrust through an opening provided in the back 3 and secured to the bottom 1 in any convenient manner, as by riveting or welding. 95

For supporting a floor brush the pan is 100 hung from the open end and clips 15 are provided which are made of a narrow strip of spring metal bent in the form of a T, as shown in Fig. 6. The portions of the metal which form the cross of the T and for a 105 short distance of the leg to a point where a bead 16 is provided are joined by soldering. From the bead 16 the separate parts of the leg are free to engage the back 3, the bead 16 engaging a bead 17 formed along the edge of 110 the back 3 when the clip is forced upon the same as shown in Fig. 4.

This form of pan may be used to support either type of sweeping device, when it is desired to support a broom the clips 15 are removed and the pan hung from the handle 5 as hereinbefore described. It is sometimes desired to suspend the broom or the like with the sweeping portion at the lower end, especially at such time when the straws or bristles are wet, and for this purpose I provide 10 a clip also formed of spring metal, the loop 20 being adapted to be sprung over the handle 4 of the dust-pan and the handle 21 of the broom being gripped by the spring fingers 22 of the clip, as pointed out in 15 Fig. 8.

It is noted that the inner side of the perforated handle which projects outwardly from the rear wall of the pan, lies, when hung on a nail passing through the said perforation, practically parallel with the wall 20 and substantially in the same plane as the bottom of the pan, while the notch in the rear wall of the pan lies substantially at right angles to the said plane. The notch is 25 made of such a size as to engage with and hold the lower part of the enlarged portion of the attachment between the broom proper and the handle, and the outer side of the handle is made of such a size as to engage 30 and lie against the upper part of the said enlargement. Thus the broom may be inserted into and securely held, and also withdrawn from the pan at will without any manipulation thereof, both of the said movements being in a horizontal direction.

The clip 20 may be used in connection with the other parts to hold the broom in a reverse position—or so that the handle will be uppermost especially when the broom is 40 wet—by the engagement of the same with the handle of the broom and also with the handle of the pan, whereby the said broom may be held in an upright or reversed position at will.

45 While I have shown and described this specific form of device it is evident that various modifications of the same may be had, and I do not wish to limit myself in the construction of the same further than is re-

quired by the state of the art and that which is within the scope of the appended claims.

I claim:

1. In a device of the class described, a pan formed with a bottom portion and side and rear walls, the rear wall having a handle 55 projecting outwardly therefrom at the lower central portion thereof and adapted to lie, together with the bottom of the pan, in a plane parallel with a wall, and the rear wall having a notch lying at right angles to said 60 plane, the handle being constructed and arranged to engage a broom to hold it at a distance from the wall, and the notch serving to sustain the broom handle practically parallel with the wall, whereby, when the pan is 65 hung up, the broom may be inserted into, and securely held, and also withdrawn from, the pan with a horizontal movement without manipulating the pan.

2. In a device of the class described, a pan 70 formed with a bottom portion and side and rear walls, the rear wall having a handle projecting outwardly therefrom at the lower central portion thereof and to lie, together with the bottom of the pan, in a plane parallel with a wall, and the rear wall having a notch lying at right angles to said plane, the 75 said handle being constructed and arranged to engage a broom to hold it at a distance from the wall, and the notch serving to sustain the broom handle practically parallel with the wall, whereby, when the pan is hung up, the broom may be inserted into, and securely held, and also withdrawn from, the pan with a horizontal movement without 80 manipulating the pan, in combination with a clip adapted, when the broom is inserted in the notch in a reverse direction, to encircle both the handle of the pan and also the handle of the broom, whereby, the broom may be held upright or in a reversed position at will.

In testimony whereof, I do affix my signature in presence of two witnesses.

EMIL E. STOSER.
